UNITED STATES PATENT OFFICE.

WASHINGTON T. CAPPS, OF BALTIMORE, MARYLAND, AND HERBERT G. MASTIN, OF POUGHKEEPSIE, NEW YORK, ASSIGNEES TO LOCOMOTIVE STOKER COMPANY, A CORPORATION OF PENNSYLVANIA.

LOCOMOTIVE STOKER.

Application filed June 24, 1922. Serial No. 570,612.

The invention relates to improvements in fuel delivering devices of the type shown in Patent No. 1,410,687, granted to N. M. Lower March 28th, 1922.

5 The objects of the invention are to provide for the easy replacement of a portion of the fuel discharging tube which is subjected to excessive wear, and to simplify the construction by forming the steam nipple 10 employed in connection with the tube as an integral part thereof.

It has been found in practice that the bottom of a tube of the type in question is sometimes rapidly worn away immediately forward of the steam nipple, by the cutting action of the steam and the abrasive action of the material impelled by it; and the invention consists in a tube having this section of its bottom removable, 20 the elbow to which the tube is attached, being provided with a suitable hand-hole through which this removable section may be passed, and it consists further in a tube having a steam nipple which is integral with 25 its bottom.

In the accompanying drawings:

Fig. 1 is a plan section of the improved distributor tube and of a detail of the elevator conduit associated therewith;

30 Fig. 2 is a detail section on the line 2—2 of Fig. 1;

Fig. 3 is a sectional view on the line 3—3 of Fig. 2; and

35 Fig. 4 is a sectional view on the line 4—4 of Fig. 2.

The distributor tube 10 is attached to the elbow 12 of the elevator conduit 11 by means of a hook bolt 13 engaged with a pair of lugs 14 (only one of which is shown) on the 40 elbow, in the usual manner. The bottom 15 of the tube is shown as being removable.

A feature of our invention consists in forming the steam nipple 16, provided with ports 17 from which issue the fuel-injecting 45 blasts, as an integral part of the tube, in this instance being cast with the removable bottom 15. Steam may be led to the nipple 16 in the usual manner, a steam pipe being connected laterally, as indicated at 18 in Figs. 50 2 and 3, and shown at 20.

A removable plate 21 is fitted into a suitable aperture in the rearward end of the tube bottom, its rearward end resting on a lug 22 and its forward end on a pair of lugs

23. A recess 24 at the forward margin of 55 the lower face of the plate 21 registers with a recess 25, formed in the upper face of the bottom 15, these two recesses serving for the admission of a suitable tool, preferably in hook form, for raising the plate 21 from its 60 seat for the purpose of removal.

The side wall of the elbow 12 is apertured, as shown at 26, to permit the insertion and removal of the plate 21, this aperture being closed by a cover plate 27, bolted to the 65 elbow, as indicated at 28, 28.

In service a portion of the steam blast impinges upon the rear end of the bottom of the tube, carrying with it some of the material being thrown into the furnace and causing excessive wear. By forming this portion of the bottom of the tube as a removable plate, as shown, replacement rendered necessary by the cutting and abrasive action can be easily and cheaply made, it being unnecessary to remove and replace either the entire tube or the entire bottom when the latter is made removable. 70 75

By forming the steam nipple as an integral part of the bottom of the tube, whether the latter be removable or not, accuracy in positioning it is assured. 80

While a practical and preferred form of construction is shown, we do not desire to be limited to this specific arrangement of 85 the parts.

We claim as our invention—

1. A distributor tube for stokers adapted to project into a fire-box and having a removable bottom section loosely interlocking 90 with the main or body section, and being insertible through the rear end of the tube without removal of the latter from the fire-box.

2. A distributor tube for stokers adapted to project into a fire-box and having a removable bottom section loosely interlocking with the main or body section, and being insertible through the rear end of the tube without removal of the latter from the fire-box, and a steam nipple permanently attached to the rear end of the bottom section. 95 100

3. A distributor tube for stokers adapted to project into a fire-box and having a removable bottom section loosely interlocking with the main or body section, and being insertible through the rear end of the tube without removal of the latter from the fire- 105

- box, the bottom section having a removable panel.
4. In combination, a fuel delivery elbow having a removable panel, a distributor tube receiving from the elbow and adapted to project into a fire-box, such tube having a removable bottom section adapted for insertion and removal through the panel opening.
5. In combination, a fuel delivery elbow having a removable panel, a distributor tube receiving from the elbow and adapted to project into a fire-box, such tube having a removable bottom section adapted for in-

sertion and removal through the panel opening, such bottom section having a steam nozzle permanently attached to its rearward end.

6. In combination, a fuel delivery elbow having a removable panel, a distributor tube receiving from the elbow and adapted to project into a fire-box, such tube having a removable bottom section adapted for insertion and removal through the panel opening, such bottom section having a removable panel.
